UNITED STATES PATENT OFFICE.

CHARLES J. KLEIN, OF MILWAUKEE, WISCONSIN, ASSIGNOR TO THE CUTLER-HAMMER MFG. CO., OF MILWAUKEE, WISCONSIN, A CORPORATION OF WISCONSIN.

ELECTRIC CANDLE AND THE LIKE.

1,417,532.

Specification of Letters Patent. Patented May 30, 1922.

Application filed June 21, 1917. Serial No. 176,036.

To all whom it may concern:

Be it known that I, CHARLES J. KLEIN, a citizen of the United States, residing at Milwaukee, in the county of Milwaukee and 5 State of Wisconsin, have invented new and useful Improvements in Electric Candles and the like, of which the following is a full, clear, concise, and exact description, reference being had to the accompanying drawing, forming a part of this specification.

This invention relates to electric candles and is particularly applicable to those having lamp socket fittings provided with switches to be located at the base of the 15 enclosing candle shells.

Various styles of cup are now marketed for candles and the like, the same varying so widely in depth as to frequently render an ordinary fitting disproportionate and to obstruct its switch operating means, and the 20 present invention has among its objects to provide a fitting which may be readily adapted to widely differing cups.

A further object is to provide a fitting 25 which may be adapted to different cups or the like by simple relative adjustment of the parts thereof and wired in a simple and expeditious manner.

Other objects and advantages will herein- 30 after appear.

In the accompanying drawing,

Figure 1 is a side elevational view partly in section, of an embodiment of the invention; while,

Fig. 2 is a similar view showing certain 35 parts of the device in dissociated relation and shifted circumferentially through an angle of approximately forty-five degrees from the position illustrated in Fig. 1.

Referring more specifically to the drawing, the same shows a candle shell 1, a cup 2 and a lamp socket fitting 3 of the candle length type disclosed in my prior application Patent No. 1,252,587, Jan. 8, 1918. The 40 fitting is provided with a lamp socket 4 and an insulating base 5 having enclosed therein a push button control switch, the push buttons 6 thereof projecting through the base of the candle shell and hence requiring positioning above the rim of the cup for accessibility.

The socket fitting is provided with a U-shaped supporting member 7, the latter having its extremities fitted into slots 8 in the 45 base of the former adjacent to the push but-

tons of the switch mechanism. Thus with the line terminals 9 of the fitting located as illustrated the member 7 leaves the same readily accessible for wiring and said member is provided with a flanged opening 10 through which the line wires may be brought to said terminals. Further, the member 7 is provided with a threaded bushing 11 in axial alignment with said opening, said bushing having slotted lugs 12 secured to said member by screws 13 whereby said member and bushing may be adjusted relatively to vary the height of the fitting support accorded thereby. Also, the lugs 12 are extended through the member 7 whereby the latter 70 co-operates with the screws 13 to insure permanent axial alignment of the bushing with said member and to increase the rigidity of the connection to withstand the strain incident to attachment of the support to a fixture. In practice the bushing 11 is preferably screwed directly upon a permanent fixture 14 with the candle cup 2 clamped therebetween, the usual clamping ring 11^a being also interposed.

By the arrangement above described it is obvious that prior to securement of the support 7 upon the fixture 14 the length of the former may be adjusted to insure proper positioning of the push buttons 6 and the lamp 85 socket 4 relatively to the candle cup 2 after assembly.

What I claim as new and desire to secure by Letters Patent is:

1. The combination with a candle shell, 90 of a lamp socket fitting therefor, a cup to receive said shell and fitting and an extensible supporting device for said shell and fitting arranged within said cup and providing for adjustment of said shell and fitting 95 relative to said cup.

2. The combination with a candle shell, 100 of a lamp socket fitting therefor, a switch carried by said fitting, a cup to receive said parts and an extensible supporting device arranged within said cup and adapted to support said shell, fitting and switch and to provide for adjustment thereof relative to said cup.

3. A lamp socket fitting including a base 105 having longitudinal recesses therein, a lamp receptacle and line terminals mounted on said base and an extensible supporting device, said device comprising relatively adjustable parts one having open sides con- 110

- tiguous to said terminals and having projections to be pushed into the longitudinal recesses in said base and the other having a threaded bushing for attachment to a fixture.
4. A lamp socket fitting including lamp engaging terminals, a supporting base therefor having line terminals and a U-shaped supporting device for said base having a conductor opening therein and an adjustable threaded bushing for attaching the same to a fixture, said bushing being axially aligned with said conductor opening.
- 10 5. A supporting device comprising a U-

shaped support having a cylindrical base 15 portion and a conductor opening therethrough, and an axially aligned threaded bushing having extensions telescopically engaging said base portion and extending through suitable openings in said support, 20 each of said extensions having a longitudinal slot and a clamping screw passing through said slot and entering said base portion for releasably securing said bushing and said support against relative axial movement. 25

In witness whereof, I have hereunto subscribed my name.

CHARLES J. KLEIN.
